UNITED STATES PATENT OFFICE

159,539

COMBINATION RADIO-PHONOGRAPH
TABLE CABINETWallace Schier, Forest Hills, and David L. Doggett,
Mount Kisco, N. Y.

Application April 8, 1948, Serial No. 145,595

Term of patent 3½ years

(Cl. D56—4)

To all whom it may concern:

Be it known that we, Wallace Schier and David L. Doggett, citizens of the United States and residing respectively at Forest Hills, in the county of Queens and State of New York, and Mount Kisco, in the county of Westchester and State of New York, have invented a new, original, and ornamental Design for a Combination Radio-Phonograph Table Cabinet, of which the following is a specification, reference being had to the accompanying drawing, forming a part thereof, in which:

Fig. 1 is a perspective view of a combination radio-phonograph table cabinet with the radio and phonograph in extended position, showing our new design.

Fig. 2 is a view similar to Fig. 1 but showing the radio and phonograph in concealed position;

Fig. 3 is a perspective view similar to Fig. 1 but taken from the opposite side.

Fig. 4 is a view similar to Fig. 3 but with the end panels extended.

The characteristic features of the present design reside in those portions shown in full lines on the drawing.

We claim:

The ornamental design for a radio-phonograph table cabinet, as shown and described.

WALLACE SCHIER.
DAVID L. DOGGETT.
